CONCRETE SPREADER

John P. Faber, Dunellen, N. J., assignor to Ran-
some Machinery Company, Dunellen, N. J., a
corporation of New Jersey

Application September 28, 1944, Serial No. 556,129

5 Claims. (Cl. 94—44)

1

This invention relates to apparatus for spreading concrete which has been deposited upon a roadway or the like, as from the usual concrete mixing apparatus, to supplant the difficult and costly manual work involved in conventional methods of distributing, spreading and leveling the concrete.

Conventional types of concrete paving machines or mixers employ a boom of considerable length which is supported by cables from the frame of the machine in which the mixing drum is mounted. This boom provides a track on which the distributing bucket runs to and from the mixer to receive and convey to points distant from the mixer the mixed concrete and dump it at convenient points, after which the concrete is spread and formed into a pavement by workmen.

The boom is pivotally mounted on the frame of the machine adjacent the discharge spout of the mixer so that it can be swung laterally to bring its outer part and the bucket thereon to different points from side to side of the road grade being paved, and the bucket is provided with means for propelling it along the boom in both directions and for tripping its bottom door at any desired point along the boom for depositing its load of mixed concrete at that point.

The tendency in recent times is to increase the capacity of the mixing drum, so that large batches of concrete can be mixed therein and discharged therefrom and the work thus expedited. Efficient and economical operation of the mixer also requires that the full batch of the drum shall be discharged therefrom in one operation so that it can be immediately recharged, and the mixing carried on while the concrete is being distributed. The use of such large capacity mixing drums makes the problem of distribution of the concrete on the roadway all the more important, notwithstanding the fact that the bucket may be discharged at any desired point within the range of the boom.

The fact that the buckets can be dumped at any point along the boom affords only a partial solution with respect to distribution of the concrete on the roadway and the formation of the concrete into a pavement. A bucket which dumps its entire contents at one point requires that the greater part of this load of concrete be spread and distributed by hand or that only a part of the batch of concrete mixed and ready for distribution be discharged into the bucket and distributed, which greatly reduces the normal output of the machine and results in serious loss to the contractor. To overcome this objection, double buckets have been employed.

In the dual bucket type of apparatus the buckets are arranged to be operated independently in association with two boom sections secured together and operating as a single boom. The

2

buckets are loaded by being presented together at the discharge spout of the mixer, and the batch of concrete is divided evenly between them as it comes from the discharge spout. One of the buckets may be drawn out on the boom and discharged or both buckets may be discharged at the same time, and at the same or different points along the boom.

When the buckets in the dual type of apparatus are moved to the dumping point and discharged separately, the boom may be swung laterally after one bucket is discharged and before the other is moved to a discharging point, so that the batch may be deposited on the grade at two points spaced from each other longitudinally or laterally, or in both directions, and a part of the manual work of spreading and placing the batch thus dispensed with. While the dual type of apparatus operates efficiently so far as division of the batch and mixing production of the drum are concerned, this type, as well as other types of mixers still requires that the concrete be spread over a considerable area, which involves a great deal of manual labor in spreading and placing it properly on the grade.

Accordingly, an object of the present invention is to provide an apparatus embodying novel plow means for expeditiously spreading concrete deposited upon a supporting surface.

Another object is to provide an apparatus embodying novel plow means for spreading concrete deposited upon a supporting surface, in which means are provided for changing the plowing angle of the plow, and in which means are incorporated for adjusting the plow relatively to the supporting surface.

A further object is to provide a concrete spreader embodying a carriage structure adapted to move along form members such as are employed in pavement construction work, to be guided thereby both as to the direction of progression of the work and vertically with respect to the roadway surface upon which the concrete is deposited, in which novel plow means are provided for spreading concrete deposited upon the roadway surface between the form members, and in which means are incorporated for propelling the plow means back and forth crosswise of the roadway surface for distributing and levelling the concrete.

The broad idea of a spreading blade in a concrete spreader, which blade is rotatable about a vertical axis while being moved transversely of a surface on which concrete is deposited, is described and claimed in my copending application Serial #566,128.

With these and other objects in view, as may appear from the accompanying specification, the invention consists of various features of construction and combination of parts, which will be first

described in connection with the accompanying drawings, showing a concrete spreader, of a preferred form embodying the invention, and the features forming the invention will be specifically pointed out in the claims.

In the drawings:

Figure 1 is a top plan view of a concrete spreader in accordance with the present invention, with a portion broken away for the sake of conciseness.

Figure 2 is a front elevational view of the structure shown in Figure 1.

Figure 3 is an end view of the concrete spreader with a portion broken away for the purpose of illustration.

Figure 4 is an elevational view of a traveler drive taken from the position indicated by line 4—4 of Figure 3.

Figure 5 is a partial sectional view of a concrete spreading plow adjusting means.

Figure 6 is a sectional view taken along the line 6—6 of Figure 5.

Figure 7 is a view taken from the position indicated by line 7—7 of Figure 2.

Figure 8 is an elevational view of a portion of the structure of Figure 5 but showing a modification incorporated therein.

Figure 9 is a partial sectional view of the structure shown in Figure 8.

Referring more particularly to the drawings, Figures 1, 2, and 3 illustrate a carriage or support 10 which is provided with flanged traction wheels 11 arranged to run on spaced, parallel form members 12 such as are used in concrete pavement construction work for defining the side limits of the pavement. The carriage 10 comprises in part two hollow frame members 13, each of which defines one side of the carriage. Each member 13 is mounted upon two legs 14, and each leg is supported by one of the traction wheels 11. The wheels 11 are attached to shafts or axles 15 which are supported in bearings 16 mounted on the respective legs.

Means for driving the traction wheels 11 include a horizontal shaft 17 which extends the full width of the carriage 10 directly above the axles 15 of the two rear wheels 11. The shaft 17 is supported in bearings 18 attached to the two frame members 13, and the shaft is provided with sprockets 19 for driving chains 20 passing around sprockets 21 attached to the two rear axles 15. To the shaft 17 and within the two frame members 13 are attached two sprockets 22 for driving chains 23 each extending horizontally inside one of the frame members toward the forward end of the carriage. Each chain 23 passes around a sprocket 24 attached to a shaft 25, the latter being supported in bearings 26 mounted inside the respective frame member 13. A sprocket 27 is attached to each shaft 25 for driving a chain 28 which passes around a sprocket 29 attached to one of the front axles 15.

The sprockets 21 and 29 are of the same diameter, and the sprockets 19, 22, 24, and 27 are also of the same diameter so that all the traction wheels 11 will be driven at the same speed. Power for driving the shaft 17 is supplied by an engine or motor 30 which is mounted on the carriage 10. A speed reducer 31, of any approved type, is connected with the engine 30, as at 32, and is provided with power take-off sprockets 33 and 34. A chain 35 passes around the sprocket 33 and a second sprocket 36 attached to the shaft 17 for driving the latter. Speed reducers of the foregoing type, including controls for controlling the transmission of power through

the two sprockets 33 and 34, are old and well known in the art and need not be described in further detail.

Means for distributing, spreading, and leveling concrete deposited upon the roadway or other supporting surface comprises a spreader or spreading unit 37. The spreader 37 is mounted on a traveler or carriage 38 which is arranged for movement back and forth along a track or guide 39, the latter extending crosswise of the carriage 40; that is, at right angles to the form members 12. The track 39 comprises two parallel but spaced I-beams 40 which are mounted on the frame members 13. The traveler 38 comprises a yoke 41 which underlies the I-beams 40 and which is provided with two upstanding walls 42, each of which is provided with two flanged wheels 43 arranged to run on the bottom flange 44 of one of the I-beams 40, with the two I-beams located between the two sets of wheels.

Back and forth movement is imparted to the traveler 38 by an endless chain 45 which passes around a drive sprocket 46 and an idler sprocket 47 rotatably mounted on one of the I-beams 40, with the sprockets so arranged as to place the straight reaches of the chain (disregarding slack) in parallelism with the flange 44 of the I-beam. An arm 48 is fixed to the yoke 41 and has a pivotal connection 49 with an arm 50 attached to one link of the chain 45. The arm 50 extends inwardly of the chain, and the pivotal connection 49 is located with its axis coincident with a straight line passing through the axes of the drive sprocket 46 and the idler sprocket 47.

It will thus be seen that as the arm 50 is carried by the lower reach of the chain 45, the traveler 38 will be moved in the same direction, and that when the arm is carried by the upper reach of the chain, the traveler will be moved in a reverse direction; also that the traveler 38 remains stationary while the arm 50 moves through the curved phases of the chain 45 in its passage around the two sprockets 46 and 47. Accordingly, unidirectional movement of the chain 45 is translated into back and forth movement of the traveler 38, which moves the spreader 37 back and forth in a horizontal path across the roadway or other surface being paved.

The spreader 37 comprises a triangularly shaped plow or body 51 when viewed according to Figure 7. Thus the plow 51 embodies two angularly related vertical side faces 52 terminating in a vertical concrete dividing edge 53. The plow 51 is attached to a vertical shaft 54 which is rotatably mounted in a tubular bearing 55, the latter being attached to the yoke 41. Upon the shaft 54 is mounted a collar 56 which has a key 57 extending into a longitudinal slot 58 in the shaft 54. A handle 59 is fixed to and extends radially from the collar 56 to permit manual turning of the plow to different plowing angles, support of the plow in desired angular positions, or reversal of the plow.

In view of the fact that the carriage 10 may be moved along the form members 12 and that the traveler 38 travels back and forth along the track 39, the latter being arranged at right angles to the form members, the spreader 37 is capable of universal movement in a horizontal plane. This provides a range of movement for the plow which permits the plow to be effectively maneuvered for distributing, spreading and leveling concrete deposited in large or small batches upon the roadway or other supporting surface.

The sprocket 46, which drives the chain 45,

is fixed to a rotary shaft 60 which is provided with a second sprocket 61. A chain 62 connects the sprocket 61 with the power take-off sprocket 34.

In Figure 5, the shaft 54 extends some distance above the collar 56 and is threaded at 63 for threaded connection with a hub 64 of a handwheel 65. Since the hub 64 rests on the collar 56 and the latter rests on the tubular bearing 55, the spreader 37 may be adjusted vertically through rotation of the handwheel 65.

Between the rear wheels 11 and the spreader 37 is mounted a strike-off blade 66 which extends at right angles to the frame members 13 and is employed for contouring the finished surface of the pavement after general distribution of the concrete by the spreader 37. The strike-off blade 66 is made in sections 67 which are arranged end to end and flatwise against a supporting angle 68. Slots 69 are provided in the sections 67 to receive bolts 70 which are threaded into or through the angle 68. Thus the individual sections 69 may be adjusted vertically to modify the contour forming characteristics of the strike-off blade 66.

The angle 68 is attached to the lower flange of an I-beam 71, and angles 72 are attached to the I-beam for engagement with the two rear legs 14 to guide the I-beam when it is raised and lowered, as when the strike-off blade is adjusted vertically in accordance with specific road building requirements, or for moving purposes. Means for raising and lowering the I-beam 71 comprise plunger rods 73 which are attached to the I-beam and operated by hydraulic cylinders 74 mounted on the two frame members 13. Carriage supported strike-off blades and hydraulic cylinder controlling means therefor are old and well known in the art and need not be described in more detail.

Figures 8 and 9 illustrate a modification in the angular adjustment means for the spreader 37, wherein the tubular bearing 55 is provided with teeth 75 which are engageable with similar teeth 76 on the collar 56. The teeth 75 and 76 are normally engaged to latch the spreader 37 against accidental rotation, but the teeth may be disengaged to permit rotation of the shaft 54 by merely lifting the handwheel 65 and the collar 56 a short distance.

It will be understood that the invention is not to be limited to the specific construction or arrangement of parts shown, but that they may be widely modified within the invention defined by the claims.

What is claimed:

1. A concrete spreader for distributing concrete deposited upon a roadway comprising a carriage adapted to move along the roadway, a horizontal guide mounted on said carriage cross-wise of the roadway, a traveler movable along said guide, a concrete spreading plow having a vertical shaft rotatably mounted on said traveler, said spreading plow being wedge-shaped with a concrete dividing edge positioned to one side of said shaft, means for rotating said shaft to adjust said spreading plow to different plowing angles, means for propelling said traveler back and forth along said guide to move the spreading plow in a horizontal path over the roadway, and means for adjusting the spreading plow toward and away from the roadway.

2. A concrete spreader for distributing concrete deposited upon a roadway comprising a carriage adapted to move along the roadway, a horizontal

guide mounted on said carriage crosswise of the roadway, a traveler movable along said guide, a vertically positioned bearing fixed to said traveler, a concrete spreading plow having a shaft rotatably mounted in said bearing, a handle connected with the shaft for rotating said shaft to adjust said spreading plow to different plowing angles, coactive latch formations on said handle and said bearing for latching the handle and said shaft 10 against accidental rotation, an endless flexible means pivotally connected with said traveler in such manner as to move the traveler back and forth along said guide through unidirectional movement of the endless flexible means for moving 15 the spreading plow back and forth in a horizontal path over the roadway, and means for driving said endless flexible means.

3. A concrete spreader for distributing concrete deposited upon a supporting surface comprising a support, a guide, a concrete spreading plow mounted on said guide for movement in a horizontal path over the supporting surface, means for propelling said spreading plow back and forth along said guide, said spreading plow being adjustably mounted on said traveler, a hand wheel 20 operatively connected with said spreading plow for adjusting the latter vertically, said spreading plow having angularly related side faces terminating in a vertical concrete parting edge, and 25 a handle connected with said spreading plow to adjust the latter to different plowing angles.

4. A concrete spreader for distributing concrete deposited upon a supporting surface comprising a movable support, a horizontal guide mounted on 30 said support, a traveler movable along said guide, a vertical bearing fixed to said traveler, a concrete spreading means located underneath said traveler and having a shaft rotatably supported in said bearing, a handle for rotating said shaft, said 35 handle being splined to said shaft for relative movement longitudinally of the shaft, a hand wheel threaded on the upper end of said shaft and resting on said handle with the latter resting on the upper end of said bearing to support said 40 concrete spreading means, and means for propelling said traveler back and forth along said guide.

5. A concrete spreader for distributing concrete deposited upon a supporting surface comprising 45 a movable support, a horizontal guide mounted on said support, a traveler movable along said guide, a vertical bearing fixed to said traveler, a concrete spreading means located underneath said traveler and having a shaft rotatably supported in said bearing, a handle for rotating said shaft, said handle being splined to said shaft for relative movement longitudinally of the shaft, a hand wheel threaded on the upper end of said shaft and resting on said handle with the latter resting on the upper end of said bearing to support said concrete spreading means, means for propelling said traveler back and forth along said guide, and coactive means on said bearing and 55 said handle for latching the latter against accidental rotation.
